UNITED STATES PATENT OFFICE.

JAMES W. COREY, OF CLEVELAND HEIGHTS, OHIO, ASSIGNOR TO THE RELIANCE ELECTRIC & ENGINEERING CO., OF CLEVELAND, OHIO, A CORPORATION OF OHIO.

RANGE DRIVE.

Application filed October 24, 1925. Serial No. 64,585.

Where a succession of machines is required for handling material, it has been fundamentally customary to provide a drive for each machine from a common source of power and 5 individually regulate the speed of each by hand or by automatic mechanical control. For instance, in the finishing of cotton cloth, the usual procedure after bleaching is to run the cloth in a continuous web through a water mangle, a cylinder drier, a Tommy Dodd for applying a paste or starch, then through another cylinder drier and a tenter. These respective machines are customarily arranged in a progressive series and a common line 10 shaft supplies power to each. A difficulty comes in however from the fact that with the varying condition of the cloth, shrinkage in some stages and stretching in others, the rate of feed as presented to the successive machines 15 varies too widely, and if the same rate of drive for all the machines be attempted the cloth piles up before some machines and at others runs so tautly as to be pulled apart. To meet this, the drive for each machine was 20 taken off the line shaft through cone-pulleys or expansion pulleys, these being kept regulated by hand control for each machine as necessary. A further advancement in the art has involved the equipment of each section 25 of the succession or range of machines with an electric drive motor, all motors running at constant speed, and to regulate the speed for each section, a cone-pulley and belt variator has been arranged between each motor 30 and its section, the variator being operated by a mechanical connection from a bar or idler roll running on the cloth just in advance of the section. On account of the steam and wet 35 conditions of such plants, such belt and cone regulator is prone to give trouble, however. More recently an all electric drive has been proposed, using adjustable speed direct current series motors, each motor being controlled by a rheostat moved by an idler similar 40 to that in the foregoing mechanical variator. It was found however that equal movements of the rheostat give very different regulatory effects when operating near top speed and at lower speeds. Also where a low 45 threading speed was wanted, this necessitated armature control and a serious difficulty entered, as the load on each motor was not a fixed percentage of its horse power, but a factor that varied from time to time on each machine and on each particular cloth treated, and

this meant a prodigious amount of resistance changing. Furthermore, there was a difficulty from too great a speed drop from no load to full load on such motors.

An all electric drive which shall be simple 60 and reliable and widely flexible so as to take care of threading speeds and all required operating speeds is therefore highly desirable.

To the accomplishment of the foregoing and related ends, the invention, then, consists of the means hereinafter fully described and particularly pointed out in the claims, the annexed drawings and the following description setting forth in detail one construction exemplifying my invention, such disclosed construction constituting, however, but one of various applications of the principle of my invention. 65 70

In said annexed drawings:—

Fig. 1 is a plan view of a range with electric drive; Fig. 2 is a wiring diagram of the electric circuits; and, Fig. 3 is a schematic view of a range showing the control means for the circuits. 75

As shown more particularly in Figs. 1 and 80 3, a combination of treating elements or machines may consist of a water mangle W, a drier D¹, a device for applying paste or starch or the like S, a second drier D² and a tenter T and a winder or reel R. Desirably also, a 85 cooling cylinder F and an atomizer A may be interposed between the tenter and winder. Arranged to drive the first section comprising the water mangle W and first drier D¹ is an electric motor 1 and for the drive of the second section comprising the paste applier S and the second drier D² is a similar motor 2 while a third motor 3 drives the last section including the tenter, etc. Each of these motors has its armature 1¹ connected in parallel on a line supplied from the armature 4¹ of a direct current generator 4. A suitable switch 5 is arranged for opening and closing this circuit, preferably the switch being actuatable by hand, also by electromagnetic means, 90 remote control being possible through make and break switches 6, 7 and 8 located conveniently to the respective motors 1, 2 and 3. This allows of opening or closing such circuit either manually at the main station point at 95 5 as desired or from any one of the respective motor stations. Interposed in the circuit to each of the motors is a circuit breaker 9 of any desired type. The fields of the aforesaid motors are connected in parallel on a line sup- 100 105 110

plied by an additional or direct current exciter generator 10, preferably of a shunt-wound type, and the field of the generator 4 is also supplied from this line, a hand operated 5 rheostat 11 being interposed for its control. In the field circuits of each of the motors 1, 2 and 3 are also interposed individual rheostats 12, 13 and 14 respectively, these having rheostat arms pivoted as indicated at 15, 16 and 17 10 respectively, the outer extensions of such arms being connected in turn to actuating rods 18, 19 and 20 respectively and these in turn being connected to dancer rolls or the like 21, 22 and 23 respectively, which are arranged to run idly upon the web of cloth C which is travelling over the guide rolls 24 and through the range. It will be noticed that these dancer rolls 21, 22 and 23 are in each instance placed just in advance of the succeeding section and by virtue of the movement of 15 such roll as may occur with the varying conditions of stretch or shrinkage in the web, each such roll will operate its rheostat. Equivalent means for actuating the rheostat 20 from the dancer roll may of course be employed, for instance, a cord from the dancer running over a roller which carries the rheostat contacts, etc.

Any suitable means for driving the generator 4 and exciter generator 10 may be employed, but in view of the fact that mills generally are wired for alternating current, I 25 ordinarily prefer to arrange an alternating current motor as indicated at 25 for the drive of these generators, conveniently these being combined on the order of a motor generator set.

The manner of operation of the system will 30 be clear. As will be seen, when current is supplied from the armature 4¹ of the generator 4, all of the motors in the range will take their main operating characteristic therefrom and as the rheostat 11 is manipulated to control the field of the generator, all of the 35 motors will correspondingly respond to the common current condition supplied. The entire line may be thrown out by the main switch 5, hand operated directly, or by operation from the remote individual stations 6, 40 7 or 8 at the motors. In this manner, in case of accident to any particular motor, a shutdown can be brought about effecting the whole plant, or an overload on any individual motor can be taken care of by its breaker 45 switch 9. I prefer to arrange these breaker switches 9 also in interlocking relation. By reason of the separate current supply to the fields of the respective motors, it will be noticed further that these are individually 50 controlled by the respective field rheostats 12, 13 and 14 which are operated by their respective dancer rolls as governed by the tension on the web at a given point. Thus as the 55 varying conditions determine, any given dancer roll will correspondingly gauge the 60

state of its rheostat and thereby weaken or strengthen the field of the corresponding motor to effect individual speed variations required. At the same time a general and common control will be exercised by virtue of 70 the conditions on the common line.

While I have illustrated the invention as applied to a cloth finishing range, it will be understood that in its general features, it is also applicable to paper machinery and certain metal working machines, in fact any location where it is desired to control the operation of machine units by a condition of the material which is feeding into such unit. 75

Other forms may be employed embodying 80 the features of my invention instead of the one here explained, change being made in the form or construction, provided the elements stated by any of the following claims or the equivalent of such stated elements be employed. 85

I therefore particularly point out and distinctly claim as my invention:—

1. In apparatus for treating a continuous web of material, the combination of successive treating sections, a dancer roll engaging the web of material in advance of each such treating section, a separate electric motor for driving each treating section, separate rheostat means controlled by each said dancer roll and connected in series with the field of the following section drive motor, a direct current generator for supplying the armatures of said motors in parallel, an overload cut-out for each motor, a main switch between said generator and said armatures, means convenient to each motor for controlling said switch, a direct current exciter generator for supplying the fields of said motors and said generator, rheostat means connected in series with the field of said generator, and means for driving said generator and said exciter generator. 90 95 100 105

2. In apparatus for treating a continuous web of material, the combination of successive treating sections, a separate electric motor for driving each treating section, separate rheostat means connected in series with the field of each motor and operated by means responsive to the tension of the web of material in advance of each treating section, a generator for supplying the armatures of said motors in parallel, an overload cut-out for each motor, a main switch between said generator and said armature, secondary means for controlling said switch convenient to each motor, a direct current exciter generator for supplying the fields of said motors and said generators, rheostat means connected in series with the field of said generator, 110 115 120 125 and means for driving said generator and said exciter generator.

3. In apparatus for treating a continuous web of material, the combination of successive treating sections, a separate electric 130

motor for driving each treating section, separate rheostat means connected in series with the field of each motor and operated by means responsive to the tension of the web 5 of material in advance of each treating section, a generator for supplying the armatures of said motors in parallel, a main switch between said generator and said armatures, means convenient to each motor for controlling said switch, an exciter generator for supplying the fields of said motors and said generators, rheostat means connected in series with the field of said generator, and means for driving said generator and said exciter 15 generator.

4. In apparatus for treating a continuous web of material, a separate electric motor for driving each treating section, separate rheostat means connected in series with the field 20 of each motor and operated by means responsive to the tension of the web of material in advance of each treating section, a generator for supplying the armatures of said motors, means for making and breaking a circuit to such armatures, an exciter generator for supplying the fields of said motors and said generators, rheostat means connected in series with the field of said generator, and means for driving said generator and 25 said exciter generator.

5. In apparatus for treating a continuous web of material, the combination of successive treating sections, a separate electric motor for driving each treating section, separate 30 rheostat means connected in series with the field of each motor and operated by means responsive to the tension of the web of material in advance of each treating section, a generator for supplying the armatures of 35 said motors, a generator for supplying the fields of said motors and said generator, rheostat means connected in series with the field of said generator, and means for driving said generator and said exciter generator.

40 6. In apparatus for treating a continuous web of material, the combination of successive treating sections, a separate electric motor for driving each treating section, separate rheostat means connected in series with the field of each motor and operated by means responsive to the tension of the web of the material in advance of each treating section, a generator for supplying the armatures of 45 said motors, means for making and breaking the circuits to such armatures, an exciter generator for supplying the fields of said motors and said generator, means for controlling the field of said generator, and means for driving said generator and said exciter.

50 7. In apparatus for treating a continuous web of material, the combination of successive 55

treating sections, a separate electric motor for driving each treating section, separate rheostat means connected in series with the field of each motor and operated by means 60 responsive to the tension of the web of material in advance of each treating section, a generator for supplying said motors, an exciter generator for supplying the fields of said motors and generator, and means for 65 controlling the field of said generator.

8. In apparatus of the character described, the combination of successive treating sections, a separate electric motor for driving each treating section, separate rheostat means 70 connected in series with the field of each motor and operated by means responsive to the tension of the material approaching each treating section, a direct current generator for supplying the armatures of said motors 75 in parallel, means for making and breaking the circuit to such armatures, an exciter generator for supplying the fields of said motors and said generator, rheostat means connected in series with the field of said generator, and means for driving said generator and said exciter.

9. In apparatus of the character described, the combination of successive treating sections, a separate electric motor for driving 80 each treating section, separate rheostat means connected in series with the field of each motor and operated by means responsive to the tension of the material approaching each treating section, a direct current generator for 85 supplying said motors, and an additional generator for supplying the fields of said motors and said generator.

10. In apparatus of the character described, the combination of a driven machine, 90 an electric motor for driving such machine, rheostat means in series with the field of said motor and operated by means responsive to the tension of material to be treated by said machine, a generator for supplying said motor, an additional source of current for supplying the field of said motor, and a common means for controlling the field of said generator and said motor.

11. In apparatus of the character described, the combination of a driven machine, 100 an electric motor for driving such machine, rheostat means in series with the field of said motor and operated by means responsive to the tension of material to be treated by said machine, a source of current for supplying said motor, and an additional source of current for the field thereof.

Signed by me this 22nd day of October, 1925.

JAMES W. COREY.
